COMBINATION DESK AND CHAIR

Arthur J. Wilkin, San Pedro, Calif.

Application September 2, 1936, Serial No. 99,112

3 Claims. (Cl. 155—188)

My invention relates generally to furniture, and more particularly to a combination desk and chair for the convenience of a person engaged in reading, writing or drafting.

5 The principal objects of my invention, are to provide a combination desk and chair that includes a pair of substantially parallel upright cabinets that provide in effect, the sides and arms of the chair, and said cabinets being provided with shelves and compartments for the accommodation of books, stationery, letter files and the like, further to arrange between said cabinets, an adjustable seat for the occupant of the combined desk and chair, further to combine 10 with the upright cabinets, a swinging table adapted to support a typewriter, a drawing board or the like, and further to combine with the cabinets various accessories for the convenience of the user of the combined desk and chair; for instance, a swinging dictionary holder, an adjustable foot and leg rest, an adjustable copy-holder and an adjustable reading lamp.

Further objects of my invention are, to provide a combined desk and chair of the character referred to that is very compact, so as to occupy 25 comparatively little floor space, the cabinets forming the sides of the chair being mounted on casters to facilitate movement from one position to another and to construct the parts of the combined desk and chair so that the same 30 may be easily and quickly disassembled and packed so as to occupy comparatively little space while in storage or during transportation.

With the foregoing and other objects in view 35 my invention consists in certain novel features of construction and arrangements of parts that will be hereinafter more fully described and claimed and illustrated in the accompanying drawings in which:

40 Fig. 1 is a top plan view of a combined desk and chair constructed in accordance with my invention.

Fig. 2 is a front elevation view.

Fig. 3 is a horizontal section taken on the line 45 3—3 of Fig. 2.

Fig. 4 is a detail section taken on the line 4—4 of Fig. 3.

Fig. 5 is an enlarged vertical section taken on the line 5—5 of Fig. 2.

50 Fig. 6 is a vertical section taken approximately on the line 6—6 of Fig. 1.

Fig. 7 is an enlarged vertical section taken on the line 7—7 of Fig. 6.

Fig. 8 is an enlarged detail section taken on 55 the line 8—8 of Fig. 6.

Fig. 9 is a detail section enlarged, taken on the line 9—9 of Fig. 1.

Fig. 10 is an enlarged detail section taken on the line 10—10 of Fig. 6.

Fig. 11 is a detail elevational view of an adjustable connection between the seat-back and the side braces therefor.

Fig. 12 is a detail section showing a drawing board adjustably mounted on the board or table that normally carries the typewriter.

Referring by numerals to the accompanying drawings, 10 and 11 designate substantially rectangular upright cabinets that function as the sides of the chair, said cabinets being preferably formed of sheet metal and each cabinet is supported by a plurality of casters 12 that enables the completed structure to be readily moved from one position to another. These cabinets have the same over-all dimensions and the space within the cabinets may be divided by shelves and partitions into compartments adapted to receive books, letter files and accessories generally utilized by writers, draftsmen and readers.

In Fig. 6 the lefthand cabinet is shown in elevation, and this cabinet is provided with three horizontally disposed shelves 13 and one vertically disposed partition 14.

The space to one side of the partition 14 is occupied by a plurality of drawers 15, preferably formed of sheet metal and adapted to contain writing material such as paper, carbon paper, cardboard, envelopes and the like.

Where the drawers are utilized for containing writing paper, sheets of carbon and the like, the front walls of the drawers are provided with apertures 16 that are extended a short distance rearwardly in the bottoms of the drawers as illustrated in Fig. 10.

Such construction enables the individual drawers to be pulled out and the ends of the sheets of paper within the withdrawn drawer to be pushed upward to facilitate removal.

Formed in the inner edges of the front walls 17 of the cabinets are vertically disposed rows of spaced apertures 18, and adapted to be removably positioned therein, are hooks 19 that are formed on the centers of rods 20. These rods are positioned in hemis that are formed in the ends of a flexible member 21 thus providing a foot and leg rest that may be disposed at different elevations between the front portions of the cabinets. (See Figs. 3 and 4.)

Positioned in the partition 14 of the lefthand cabinet adjacent the inside face of said cabinet is a tube 22, and mounted to rotate freely therein,

is the lower portion of a vertically disposed shaft 23. Carried by this shaft just above the top of the cabinet, is the upper race 24 of a ball bearing that rests on balls and the latter bearing on a lower race 25 that is fixed on top of the cabinet.

Secured to shaft 23 just above upper race 24, is a horizontally disposed table 26 that provides a support for a typewriting machine T, and secured to the under side of this table are rubber studs 27 that form feet that rest on top of the front portions of the cabinets, thus cushioning the table when the writing machine is positioned thereupon. Obviously, table 26 may be utilized as a support for writing paper or for drawing paper. Secured on the upper surface of the table 26 at the end opposite the end that is connected to shaft 23, is a handle 28 by means of which the table may be conveniently swung from one position to another.

In Figs. 1 and 6 the table is shown in an out-of-the-way position above the front end of the lefthand cabinet, and dotted lines in Fig. 1 show the table swung into position so as to span the space between the front portions of the cabinets.

The upper portion of shaft 23 is threaded and said threaded portion extends through an aperture 29 that is formed in a flange 30 at the lower end of an upwardly projecting inclined copy-holder 31, and positioned on the threaded portion of the shaft above and below said flange 30 are nuts 32.

Such construction enables the copy-holder to be raised or lowered to the desired convenient position. Projecting horizontally from the upper end of copy-holder 31 is a flange 33 in which is formed an aperture 34.

Mounted to rotate in aperture 34 is a tubular fitting 35, and seated in the upper end of this fitting is one end of a flexible tube 36, the opposite end of which carries an electric lamp 37 and a reflector 38. The lower portion of fitting 35 that projects through aperture 34 is threaded for the reception of a nut 40, which nut engages a washer 41 that is positioned against the under side of flange 33, and electric conductors 42 lead from a suitable source of current supply through the fitting 35 and through the flexible conduit 36 to lamp 37.

By loosening nut 40, the flexible conduit 36 carrying the electric lamp may be swung into any desired position and locked in such position after such movement by tightening the nut 40.

Seated in the outer portion of the partition 14a in the righthand cabinet, and which partition corresponds with the partition 14 in the lefthand cabinet, is a tube 43 that provides a bearing for a vertically disposed shaft 44, and projecting upwardly and inclined from said shaft 44 is an arm 45. The upper end of this arm is positioned between brackets 46 that are secured to the under side of an inclined holder 47 that is adapted to receive a large book such as a dictionary and passing through said brackets 46 and the upper end of arm 45, is a bolt 48, the threaded end of which receives a winged nut 49.

The construction just described provides means whereby the book support 47 may be swung about the axis formed by the shaft 44, and said support may be shifted into different inclined positions and locked after such adjustment by tightening winged nut 49 on the bolt 48.

Positioned directly against the inner edges of the shelves 13 of both cabinets are vertically disposed seat hangers comprising straps 50 on

which are formed inverted L-shaped hooks 51 that engage over beads on the edges of said shelves.

These straps are for the support of the adjustable seat and the members of the front pair of straps are disposed near the centers of the cabinets while the members of the rear pair of straps are positioned adjacent the rear ends of said cabinets. These straps are retained in position on the shelves by means of screws 52 which pass through the intermediate portions of said straps and engage beneath the edges of the adjacent shelves. Formed through the upper portions of the straps 50 are apertures 53 for the accommodation of the bolts that adjustably secure the seat to the straps.

The seat comprises a suitable framework, preferably formed of metal, and which includes a pair of transverse channels 54, the ends of which are bent downwardly at right angles so as to lie directly against the faces of the straps 50. The downwardly bent ends of these channels are provided with perforations that receive bolts 55, and which latter pass through any of the apertures 53 so as to connect the transverse channels 54 to the straps 50 and the threaded ends of said bolts receive winged nuts 56.

Supported by the end portions of the transverse channels 54 are longitudinally disposed rails 57, which in turn support a panel 58, preferably of metal, that provides a seat.

Connected by a hinge 59 to the rear end of the seat is an upwardly and rearwardly projecting seat-back 60, and secured to the sides thereof, are staples 61. Passing through each staple 61 is a toothed bar 62, the teeth of which are adapted to engage the lower portion of the corresponding staple and the forward lower end of each bar is pivotally connected to an arm 63, the forward lower end of which is pivotally connected to the intermediate portion of the side of the seat frame.

The construction just described provides simple and effective means for adjusting the angularity of the seat-back, and to firmly hold the same in its adjusted position. When the toothed rails 62 occupy inclined positions, as illustrated in Fig. 6 and by solid lines in Fig. 11, the rails cannot move upward a sufficient distance to disengage the teeth from the lower portions of the staples 61.

When it is desired to change the inclination of the set-back, the rear ends of the arms 63 are swung upwardly and forwardly thereby swinging the notched bars 62 into practically horizontal planes or positions substantially at right angles to the plane occupied by the staples 61, and when so positioned the notched bars may be lifted a sufficient distance to disengage the teeth thereof from the lower portions of the staples 60 and thus permitting said bars to be moved forwardly or backwardly to effect the desired adjustment.

The position of the toothed bar when shifted as just described, is illustrated by dotted lines in Fig. 11.

In Fig. 12 I have illustrated a drawing board adjustably mounted on a modified table that supports the typewriter and in this construction the ends of the modified table 26a are extended upwardly to form ears 65 that are perforated as designated by 66 and passing through said perforations are bolts 67 that also pass through apertures in brackets 68 that are secured to and depend from the under side of a drawing board 75

69. Except as mentioned above the table 26a is the same and is mounted in the same manner as the table 26.

By providing a plurality of apertures in the ears 65, the drawing board 69 may be adjusted vertically for a certain distance and the bolts 67 provide an axis upon which the board may be tilted to adjust its inclined position.

Thus it will be seen that I have provided a relatively simple, practical and inexpensive combination desk and seat that is particularly applicable for the use of persons engaged in reading, writing, drawing and the like, and the cabinets that form the sides or arms of the seat being provided with shelves and compartments for the accommodation of books, writing material and accessories generally used by the occupant of the seat.

The table that provides a support for a typewriting machine or the like, may be readily swung so as to bring the typewriting machine into and out of position for use and the occupant of the seat between the cabinets may conveniently reach all of the equipment and accessories that are mounted upon and stored within the cabinets.

Thus it will be understood that minor changes in the size, form and construction of the various parts of my improved combination desk

and chair may be made and substituted for those herein shown and described without departing from the spirit of the invention, the scope of which is set forth in the appended claims.

I claim as my invention:

1. A knockdown article of furniture, comprising a spaced pair of cabinets provided with inwardly facing shelves and storage compartments, opposed and vertically disposed seat mounting hangers removably secured to shelves of each cabinet, a seat removably and adjustably secured to said hangers between said cabinets, said cabinets having the same over-all size and shape to permit the consolidation thereof into a compact assembly for convenient storage upon the removal of said seat.

2. The structure of claim 1, said hangers each having a plurality of spaced apertures formed therein, and said seat having means adapted for selective seating in said apertures.

3. The structure of claim 1, said hangers each having a plurality of spaced apertures formed therein, and said seat having means adapted for selective seating in said apertures, and means connecting the front portions of said cabinets together, said means comprising a removable foot rest.

ARTHUR J. WILKIN.
